UNITED STATES PATENT OFFICE.

HANS WEIDE, OF BROOKLYN, NEW YORK, ASSIGNOR TO LORENZ & WEIDE,
OF NEW YORK, N. Y.

HOLDER OR CABINET FOR CARRYING TALKING-MACHINE RECORDS.

Application filed August 4, 1921. Serial No. 489,676.

To all whom it may concern:

Be it known that I, HANS WEIDE, a citizen of the United States, and resident of Brooklyn, in the county of Kings and State of New York, have invented certain new and useful Improvements in Holders or Cabinets for Carrying Talking-Machine Records, of which the following is a specification.

This invention relates to a holder or cabinet for talking machine records adapted to hold the records ready for individual withdrawal as desired.

The present invention is a further development of one disclosed by me in a previous application for patent filed by me on July 5, 1921, Serial No. 482,482. In this previous application a base or support for holding the records in upright position is shown, the present application having more particular reference to a housing carried by the base and adapted to cover the records.

The invention has for a general object to provide a record holder or cabinet arranged to facilitate access to, and withdrawal of, the records.

More specifically speaking the invention has for an object to provide a housing or casing having a novel arrangement of hinged wall members to facilitate.

For further comprehension of the invention, and of the objects and advantages thereof, reference will be had to the following description and accompanying drawings, and to the appended claims in which the various novel features of the invention are more particularly set forth.

Figure 1 of the drawings is a perspective view of a record holder constructed according to the invention, showing the hinged cover member swung partially back.

Figure 2 is a transverse vertical sectional view thereof, this view being taken on the line 2-2 of Figure 3.

Figure 3 is an enlarged horizontal section on the line 3-3 of Figure 2.

Figure 4 is a longitudinal sectional view of the base alone, this view being taken along the line 4-4 of Figure 3.

As here shown my improved record holder comprises a rectangular base 10, of considerable thickness, in the top of which are formed two series of grooves or slots 11 and 12 respectively extending in a general direction longitudinally of the base and adapted to receive the edges of the records R

therein to support the latter in upright position.

Each series of grooves terminates at one end a short distance from the adjacent end of the base and is cut through the opposite end of the base, the respective series of grooves being cut through opposite ends of the base.

The respective grooves of each series diverge, or spread out in the direction of the ends thereof which are cut through the end of the base. This base as thus described forms the subject matter of my previous application above referred to.

The records supported in the respective series of grooves are adapted to be removed from opposite ends of the base, the housing or casing to which the present invention has particular reference being designed to open in a manner to permit of this.

As here embodied this housing comprises a pair of side walls 15, 16 fixed at their lower edges to the side of the base 10, the wall 15 extending the full height of the housing, while the wall 16 is one-half the height thereof. The upper edge of wall 16 has hinged thereto the cover element of the housing which comprises a side member 18 complementary to the upper half of the other side wall, a top member 19, and a pair of end wall members 20, all joined in a rigid structure.

As will be apparent, when the cover element is in closed position a completely closed housing or cabinet is provided, while this box may be opened at the top and ends by simply swinging the cover element on its hinges to the position shown in dot and dash lines in Figure 2, permitting the records to be withdrawn from either end as desired.

Having thus described my invention what I claim as new and desire to protect by Letters Patent of the United States is as follows:

1. A record holding cabinet comprising a bottom section and a top section hinged thereto, the top section forming the entire top and end walls of the cabinet whereby the top section when swung to open position upon the hinges will permit the records to be removed laterally from the cabinet.

2. A record holding cabinet comprising a bottom section having a bottom wall and side walls, and a section hinged to said bottom section comprising a top wall and end

walls whereby a completely closed container adapted to be used as a drawer is provided and said top section provided with a handle whereby said container may be used as 5 a portable unit.

3. A record holding cabinet comprising a bottom section and a top section hinged thereto, said bottom section comprising a bottom wall and side walls one of said side 10 walls extending the full height of said cabinet and the other of said side walls extending substantially half the height of said cabinet, said top section comprising a top wall, end walls and a side wall, said top 15 side wall being hinged to the shorter of said bottom side walls, said end walls extending the full height of said cabinet, and said bottom wall provided with a plurality of spaced grooves to receive the records and 20 hold them in spaced condition within said container.

4. In a record holding cabinet, fixed side walls one of which is of less height than the height of the cabinet, an upper side wall 25 section hinged to said last mentioned wall, and top and end wall members fixed to said upper section, said end wall members extending downward along the ends of the fixed wall to which said upper section is 30 hinged.

5. A record holding cabinet comprising a bottom section and a top section hinged thereto, said bottom section comprising a bottom wall and side walls, one of said side 35 walls extending the full height of said cabinet and the other of said side walls extending substantially half the height of said cabinet, said top section comprising a top wall, end walls and a side wall, said top 40 side wall being hinged to the shorter of said bottom side walls, said end walls extending the full height of said cabinet and said bottom wall provided with a plurality of 45 spaced grooves adapted to receive and hold the records in spaced condition within said container said grooves inclined downwardly and terminating in a curved surface to hold the records substantially centrally of said end walls.

6. In a record holding cabinet, a base, 50 fixed side walls one of which extends the full height of the cabinet, and the other approximately one half the height of the cabinet, an upper side wall section hinged to the upper edge of the last mentioned fixed wall, 55 and top and end wall members fixed to said hinged section, said end wall members extending the full height of the cabinet.

7. In a record holding cabinet, a base, 60 fixed side walls one of which extends the full height of the cabinet, and the other approximately one half the height of the cabinet, an upper side wall section hinged to the upper edge of the last mentioned fixed wall, 65 and top and end wall members fixed to said hinged section, said end wall members extending the full height of the cabinet, and projecting across the ends of said base and fixed walls.

8. A record holding cabinet comprising a 70 bottom section and a top section hinged thereto, said bottom section comprising a bottom wall and side walls, one of said side walls extending the full height of said cabinet and the other of said side walls extending substantially half the height of said cabinet, said top section comprising a top wall, end walls and a side wall, said top side wall being hinged to the shorter of said 75 bottom side walls, said end walls extending the full height of said cabinet, and said bottom wall provided with a plurality of 80 spaced grooves to receive the records and hold them in spaced condition within said container, said grooves being arranged in two sets of oppositely diverging groups, one group of grooves extending to one end of 85 said bottom wall and the other group of grooves extending to the other end of said bottom wall, and all of said grooves inclining downwardly towards the center of said bottom wall and terminating in a curved surface adapted to hold the records substantially centrally of the ends of the container.

Signed at New York, in the county of 90 New York and State of New York, this 28 day of July A. D. 1921.

HANS WEIDE
